UNITED STATES PATENT OFFICE.

MARSHAL WALLACE, OF LITTLE ROCK, ARKANSAS.

SEPARATOR FOR COTTON-SEED-OIL MILLS.

SPECIFICATION forming part of Letters Patent No. 366,540, dated July 12, 1887.

Application filed August 20, 1886. Serial No. 211,420. (No model.)

To all whom it may concern:

Be it known that I, MARSHAL WALLACE, a citizen of the United States, and a resident of Little Rock, in the county of Pulaski and State 5 of Arkansas, have invented certain new and useful Improvements in Separators for Cotton-Seed-Oil Mills; and I do declare the following to be a full, clear, and exact description of the invention, such as will enable others skilled in 10 the art to which it appertains to make and use the same, reference being had to the accompanying drawings, and to letters or figures of reference marked thereon, which form a part of this specification.

15 Figure 1 of the drawings is an end elevation, partly in section and partly broken away, of my improved separator, &c. Fig. 2 is a side view of the same, partly broken away to better show the operating parts. Fig. 3 is an en- 20 larged face view of one of the beaters, and Fig. 4 is a side view of the same.

My invention relates to separators designed for use in cotton-seed-oil mills and other places for the purpose of separating cotton-seed meal 25 from the hulls after the seed has been ground, and for cleaning sand and other impurities from the cotton-seed meal; and the invention consists in the construction and novel combination of parts, as hereinafter described, and 30 pointed out in the claim.

Referring by letter to the accompanying drawings, A designates the rectangular case or box in which the beaters, screen, brushes, and conveyer are placed, said box being pro- 35 vided on its top, near its front end, with a feed-hopper, B, at the discharge end of the screen C, with a discharge-chute, D, through which the hulls of the cotton-seed are dis- 40 charged, and at the discharge end of the conveyer with meal-discharge chutes E F, through which the cotton-seed meal is discharged into any suitable receptacle. I may use only one conveyer, G, or I may use two conveyers, ar- 45 ranged side by side, and instead of locating the meal-discharge chute or chutes at the end of the conveyer I may locate it or them intermediate of the ends of said conveyer, if I so elect.

H designates the beater-shaft, which is mounted in bearings in the ends of the box or 50 case, and is provided at one end with a driving-pulley, I, by means of which power is im- panted to drive the shaft. Near the driving-

pulley I the beater-shaft H is provided with a sprocket-wheel, J, which is connected by a sprocket-chain, K, with a sprocket-wheel, L, 55 on the conveyer-shaft M. The beater-shaft H is provided with radially-extending beaters N, the threaded ends of which are screwed into seats in the beater-shaft, said seats being ar- ranged spirally around the beater-shaft. The 60 outer ends of the beaters are flattened into paddle or fan shape. The beaters are arranged with their blades alternately at right angles to the axis of the rotating beater shaft and parallel with said axis. 65

C indicates a concave metallic screen, which is arranged in the beater frame or case concentric with and below the beater-shaft. The longitudinal edges of this screen are secured to the side walls of the case to sustain the same 70 in position.

Below the concave screen C, at opposite sides thereof, and arranged to slide in bearings in the frame of the box or bin, are the brush-supporting rods P P, having the corre- 75 sponding ends of the longitudinal series of brushes Q Q R on each side secured to them, so that the said rods and brushes reciprocate together. The brushes are preferably equi- 80 distant, and are made on the arcs of similar 85 circles concentric with the beater-shaft H, and when reciprocating with the rods P move longitudinally upon the lower surface of the screen C and prevent the meshes thereof from being clogged by the material. It is obvious 90 that these brushes, or their frames, which are placed on the supporting rods P P, may be se- 95 cured thereto by set-screws or other common fastening devices.

One of the brushes (designated by R) is con- 90 nected through its depending arm S to the in- 95 nner end of a pitman-rod, T, the outer end of said pitman-rod T being connected to a crank consisting of the disk t and wrist-pin t' at the upper end of a vertical shaft, J', supported in suitable bearings at the front end of the box or case, and provided with a miter-gear, V, which engages a miter-gear, W, on the end of the conveyer-shaft and operates the brush- 100 supporting rods and brushes.

The pitman-rod may be operated by hand, if desired, in which event the miter-gearing and crank-shaft may be disconnected, or omitted entirely, if desired.

The ground cotton-seed is introduced at the feed-hopper, and the beaters act as conveyers and also as fans, and convey the meal and hulls in the direction toward the rear end of the shaft over the perforated bottom. Every alternate beater acts as a fan, so that wet or damp hulls are cleaned, as the fans cool and dry the coagulated meal that adheres to the wet hulls and the beaters separate the meal from the hulls while the latter are traveling over the screen. The sprocket-wheels J and M and chain K cause the conveyer-shaft to rotate simultaneously with the beater-shaft, so that by means of the bevel-gears V and W and the crank and pitman T the brushes Q are reciprocated under the concave screen C only at the time that the beater-shaft is rotating. Thus while the machine is cleaning and separating the materials the brushes prevent the meshes of the screen from being clogged, so that the parts coact.

Having described this invention, what I claim, and desire to secure by Letters Patent, is—

In a separator for a cotton-seed-oil mill, the combination, with the longitudinal screen made transversely on the arc of a circle, the shaft concentric with said screen, and the beaters secured to the shaft in spiral lines, of the single series of equidistant curved brushes concentric with and resting against the under surface of the screen, the reciprocating side rods having the ends of the brushes secured to them, and mechanism, substantially as described, whereby the brushes and rods are reciprocated, substantially as specified. 35

In testimony whereof I affix my signature in presence of two witnesses.

MARSHAL WALLACE.
